UNITED STATES PATENT OFFICE.

JOE M. MCCOMAS, OF EDGERTON, MISSOURI.

DESIGN FOR A METALLIC RIM FOR FACE-GLASSES OF BURIAL-CASKETS.

SPECIFICATION forming part of Design No. 36,146, dated November 18, 1902.

Application filed August 25, 1902. Serial No. 121,010. Term of patent 14 years.

To all whom it may concern:

Be it known that I, JOE M. MCCOMAS, a citizen of the United States, residing at Edgerton, in the county of Platte and State of Missouri, have invented a new, original, and ornamental Design for a Metallic Rim for Face-Glasses of Burial-Caskets, of which the following is a specification.

The figure is a plan view of a rim for face-glasses of burial-caskets, showing my new and ornamental design.

The leading or material feature of my design consists of the conventional representation of climbing vines 5 6 upon a substantially rectangular frame 1. The upper two corners of the frame are cut off obliquely, as

shown. The stems 5 of the represented vines start and branch off from the rectangular corners of the frame.

Having described my invention, what I claim as new, and desire to secure by Letters Patent of the United States, is—

The ornamental design for a metallic rim for face-glasses of burial-caskets, as herein shown and described.

In testimony whereof I affix my signature in the presence of two witnesses.

JOE M. MCCOMAS.

Witnesses:

W. L. LANGE,
A. W. HIRSCH.
